UNITED STATES PATENT OFFICE.

ALBERT N. FRIES, OF CHICAGO, ILLINOIS.

SHADE-FIXTURE.

1,203,524.

Specification of Letters Patent.

Patented Oct. 31, 1916.

Application filed June 11, 1914. Serial No. 844,449.

To all whom it may concern:

Be it known that I, ALBERT N. FRIES, a citizen of the United States, and a resident of the city of Chicago, county of Cook, and 5 State of Illinois, have invented certain new and useful Improvements in Shade-Fixtures, of which the following is a specification.

My invention relates to shade fixtures, and more specifically to a device for adjustably 10 supporting a shade roller so as to permit of vertical adjustment of the latter in order to so position the shade as to secure the shade desired, and at the same time, to permit of the passage of light above or below the 15 shade, and to permit of free ventilation where the windows are open.

A further object is the production of a shade fixture as mentioned, which will be of simple construction and efficient in use.

20 Other objects will appear hereinafter.

With these objects in view, the invention consists in the combinations and arrangements of parts hereinafter described and claimed.

25 The invention will be best understood by reference to the accompanying drawings forming a part of this specification, and in which,

Figure 1 is a perspective view of a window 30 equipped with a shade fixture embodying my invention, Fig. 2 is a central longitudinal section of the hanger of the device detached, Fig. 3 is a perspective view of one end of the hanger, Figs. 4 and 5 are enlarged transverse 35 sections taken on lines $x-x$ and $y-y$ respectively of Fig. 2, Fig. 6 is a top plan view of another form of the hanger, Fig. 7 is a central longitudinal section of the form shown in Fig. 6, Fig. 8 is an enlarged transverse section taken on line $z-z$ of Fig. 7, 40 and Fig. 9 is a fragmental central section of one end of the hanger equipped with a guide roller which may be used in connection therewith if desired.

45 The preferred form of construction as illustrated in the drawings, comprises an elongated hanger which is formed of two sheet metal sections 1 and 2, the inner ends of said sections being telescoped so as to 50 permit of relative sliding of said sections in order to adjust the hanger longitudinally, so as to adapt the same to accommodate shade rollers of various lengths. The hanger section 2 is provided at its lower edges with 55 outwardly and upwardly turned flanges 3 which slidably embrace the corresponding

edges of section 1, said sections being substantially semi-circular in cross section in order to inclose the upper portion of the shade roller A arranged therein, and the 60 upper side of the hanger is formed with a longitudinally extending rib or channel in order to reinforce or stiffen the same. At the outer end of each of the hanger sections are provided inwardly extending ears 4 65 which are rigidly connected together by an eyelet, the eyelets at the opposite ends of the hangers forming openings 5 and 5' for engagement with the respective ends of the 70 studs of the shade roller.

The hanger is suspended by means of a cord or flexible element 6, one end of which engages with a channel member 7 which is mounted upon the hanger intermediate the 75 ends thereof, said member 7 being provided at its lower edges with inwardly and upwardly turned flanges 8 which slidably embrace the lower edges of the section 2. Said member 7 is releasably locked in position by means of screws 9 which engage against the 80 upper side of hanger section 1. The arrangement is such, that the member 7 may be adjusted longitudinally of the hanger in order to position the same centrally of the hanger after the latter has been adjusted 85 longitudinally in order to accommodate a shade roller of a particular length, said member 7, after being adjusted to the center of the hanger, being secured in this position by means of screws 9. The end of cord 6 90 engaging with the member 7 passes through an opening 10 provided in the upper side of said member, said cord being provided at its lower end with a knot as shown, which serves to lock said cord against upward movement 95 through the opening 10.

In order to prevent wear of the cord by reason of engagement thereof with the edges of opening 10, a metallic sleeve or bushing 11 is provided upon the cord immediately 100 above the knot thereof, as clearly shown in Fig. 4. With this arrangement, it will be seen, that the member 11 will take up all wear and thus extend the life of the cord. At the front side of the member 7 is provided an opening 12 through which the cord 105 may be passed in order to effect engagement thereof with the opening 10 or disengagement of said cord from said opening, said opening 12 being large enough to permit the passage of the knot provided at the lower end of said cord. The upper side of 110

the member 7 is spaced from the upper side of the hanger, as shown, so as to permit of the uninterrupted passage of the cord from opening 10 to opening 12 and vice versa.

5 The cord 6 passes upwardly from the member 7 over a pulley 13 of the usual catch-roller type in common use at the present time which is adapted to engage and clamp the cord at any point desired, the construction of this pulley being well known so as to not require detail description. After passing over the pulley 13, which is secured centrally to the upper end of the window frame, the cord passes downwardly under a pulley 13' of corresponding form, which is secured centrally to the lower end of the window frame, after which said cord passes upwardly for engagement with the lower end of the window shade, as clearly shown in 10 Fig. 1.

15 Slidably mounted at the upper side of the hanger is a channel member 14 having inwardly and upwardly turned flanges 15 at its lower edges which embrace the lower edges of section 2. Arranged in the upper side of the member 14 is a weight 16 secured thereto by means of a screw 17, said screw serving also as a means of securing the member 14 in positions of longitudinal adjustment upon the hanger. The member 14 and the weight member 16 carried thereby, serve as a means of counterbalancing the weight of the actuating spring of the shade roller, this spring being usually mounted in one 20 end of the roller. Without the provision of counterbalancing means, the weight of the actuating spring of the roller would cause one end of the latter to rock downwardly so as to destroy the operative horizontal position of the shade and preclude the possibility of the shade being readily rolled thereon. With the provision of the counterbalancing device as mentioned, after the shade roller has been mounted in the hanger, 25 the member 16 needs only to be slid longitudinally upon the hanger until the hanger is so balanced as to assume a horizontal position whereupon said member 16 is locked by tightening the screw 17. With this arrangement then, it will be seen that the proper horizontal position of the hanger and shade roller carried thereby may be readily maintained.

30 Provided at the ends of the hanger and at the rearward side thereof, or at the points where said hanger engages against or contacts with the window frame, are projecting studs 18 covered with plush or other anti-friction or nonabrasive material which serve 35 as a protection to prevent marring of the window frame in the vertical adjustment of the shade hanger.

35 In the form shown in Figs. 6, 7 and 8, the hanger is formed of telescoping sections 1' and 2', the section 1' being provided at its

lower edges with inwardly and upwardly turned flanges 3' which slidably embrace the corresponding edges of section 2', the arrangement being substantially the same as that before described. At the outer ends of 40 the sections 1' and 2' are provided inwardly extending ears 4' in which are formed the sockets or openings 5 and 5' for engagement with the shade roller studs, as above set forth. In this form, however, the members 7 and 16 are dispensed with and in lieu of the former, a bar 19 is arranged in the reinforcing rib provided at the upper side of the hanger, being secured in position 45 therein by means of screws 20 and co-operating nuts, said screws passing through elongated registering slots 21 provided in the upper sides of hanger sections 1' and 2'. The member 19 is provided medially of the ends thereof with an opening 22 for engagement with the lower end of the suspending cord 6, said cord engaging with the opening 22 in precisely the same manner as the same engages with the opening 10 of the member 7, above described. In this form, 50 however, it will be seen that engagement of the cord 6 with the hanger, or disengagement thereof from the hanger may be effected only when the shade roller is detached, which is not the case in the form 55 first described where connection or disconnection of the suspending cord may be effected without disturbing the shade roller which may be mounted in the hanger.

55 In lieu of the counterbalancing device of the form first described, in the modified form a counterbalancing weight 23 is employed which is slidably mounted in the rib provided at the upper side of the hanger, being secured in positions of adjustment by 60 means of screws 24 which pass through the slots 21. In the form last described, it will be seen that the member with which the suspending cord is connected, and the counterbalancing device, are concealed within the 65 hanger which results in a neat and pleasing design.

70 Where the device is used in railway cars, or in connection with windows having vertical grooves at the inner sides of the vertical bars of the frames thereof, the hanger will be provided with rollers 25 at the respective ends thereof for engagement with said grooves, in order to guide the hanger in its vertical movement. The rollers 25 75 are mounted at the ends of the hanger so that the outer portions thereof project from the corresponding end surfaces of the hanger, as clearly shown in Fig. 9, in order to adapt said rollers for engagement with the window frame grooves, as will be readily understood.

75 While I have illustrated and described the preferred forms of construction for carrying my invention into effect, these are capa- 80

ble of variation and modification without departing from the spirit of the invention. I, therefore, do not wish to be limited to the precise details of construction set forth, but desire to avail myself of such variations and modifications as come within the scope of the appended claim.

Having described my invention what I claim as new and desire to secure by Letters Patent is:

A shade fixture comprising a channel formed hanger with its open side facing down, means in said hanger for supporting a shade roller therein; a flexible suspending element; an adjustable connection between said suspending element and said hanger permitting of the point of connection between said element and said hanger being shifted longitudinally of the latter, said means comprising a member of substantially inverted U-shape, the ends of said member embracing the longitudinal edges of said hanger, the central portion of said member being spaced from the upper side of said

hanger and having an opening in the upper portion thereof through which the lower end of said suspending element extends; an enlargement at the lower end of said suspending element of greater diameter than said opening and adapted to engage against the under side of said upper portion of said member, there being an opening in the front side of said member adapted to permit of the passage of said suspending element in engaging the same with or disengaging the same from said first mentioned opening, said last mentioned opening being of greater diameter than said enlargement, and clamping screws threaded in said member and contacting with said hanger substantially as described.

In testimony whereof I have signed my name to this specification in the presence of two subscribing witnesses.

ALBERT N. FRIES.
